(57) **CLAIM**

The ornamental design for a scoop, as shown and described.

DESCRIPTION

FIG. 1 is a top, front, right-side perspective view of a scoop showing our new design.

FIG. 2 is a front view of the scoop of FIG. 1.

FIG. 3 is a rear view of the scoop of FIG. 1.

FIG. 4 is a right-side view of the scoop of FIG. 1.

FIG. 5 is a left-side view of the scoop of FIG. 1.

FIG. 6 is a top view of the scoop of FIG. 1; and,

FIG. 7 is a bottom view of the scoop of FIG. 1.

The short broken lines showing elements of the scoop in the drawings illustrate features of the article of manufacture that form no part of the claimed design. The broken lines consisting of dot-dash lines are boundary lines that show that the claimed design extends to the boundary line, but does not include the boundary line.
